[57] CLAIM

The ornamental design for a bird feeder, as shown and described.

DESCRIPTION

FIG. 1 is a perspective view of a bird feeder showing my new design;

FIG. 2 is a front elevational view thereof, the rear being the same as the front shown;

FIG. 3 is an elevational view taken from one side thereof, the opposite side being the same as the side shown;

FIG. 4 is a bottom plan view thereof;

FIG. 5 is a top plan view thereof;

FIG. 6 is a front elevational view of a modified form of the bird feeder shown in FIG. 1, the rear being the same as the front shown;

FIG. 7 is an elevational view taken from one side of FIG. 6, the opposite side being the same as the side shown;

FIG. 8 is a bottom plan view of FIG. 6; and

FIG. 9 is a top plan view of FIG. 6.
